UNITED STATES PATENT OFFICE.

BARNEY B. RICE, OF REDLANDS, CALIFORNIA.

GRIPPER FOR JOB PRESSES.

1,402,090.

Specification of Letters Patent. Patented Jan. 3, 1922.

Application filed April 29, 1920. Serial No. 377,554.

To all whom it may concern:

Be it known that I, BARNEY B. RICE, a citizen of the United States, residing in the city of Redlands and State of California, have invented new and useful Improvements in Grippers for Job Presses, of which the following is a specification, reference being had to the accompanying drawings.

The present invention pertains to grippers for job presses, and the prime object is to provide an improved gripper which embodies a cross bar at the outer end of the gripper, designed to facilitate the work of the gripper and to prevent the buckling of the paper in the process of printing.

It is well known amongst printers that as ordinarily constructed the free ends of the gripper permit the paper to buckle or stick to the type while being run through the press. The present invention will obviate this difficulty.

A practical embodiment of the invention is illustrated in the accompanying drawings, wherein:

25 Figure 1 is a plain view.

Figure 2, a side elevation.

Figure 3, a detail showing the method of locking the cross bar to the ends of the gripper.

30 The invention consists in cutting a series of transversely aligned, vertical slots as 1, 2, and 3, longitudinally along each of the gripper arms 4, said gripper arms being of the ordinary kind as now used. An auxiliary cross bar 5 is provided which is recessed at its ends, as shown at 6, to receive

35 the outer ends of the gripper arms 4, and so that said outer ends will set snugly up with-

in the recesses 6 while the lower edge 7 of the cross bar will fall near the lower sides 40 of the gripper arms 4. The cross bar 5 is then adjustably secured in place by means of suitable screws 8.

The cross bar 5 may, of course, be locked in place between any two of the oppositely 45 disposed slots 1, 2, and 3, so as to adjust the cross bar in the direction of its movement to any sized sheets of paper which may be run through the press. The cross bars may likewise be made of different lengths to adjust 50 the gripper arms for the same purpose in the other direction.

While I have herein described a certain specific method of constructing and assembling the elements of my invention, it 55 is understood same may be varied in minor details, not departing from the spirit of my invention as defined in the appended claim.

What I claim to be new and patentable is:

A gripper for printing presses including 60 spaced gripper arms provided at intervals in their outer faces with transversely aligned recesses and having relatively short longitudinal slots located in the said recesses, an adjustable cross bar connecting the said 65 arms and having its terminals arranged in two of the said recesses, and fastening devices piercing the cross bar and passing through the adjacent slots of the gripper arms and adapted to secure the cross bar in 70 any of the transversely aligned recesses.

BARNEY B. RICE.
